Inventor:

John A. Thompson

United States Patent Office.

JOHN A. THOMPSON, OF AUBURN, NEW YORK.

Letters Patent No. 101,943, dated April 12, 1870; antedated April 1, 1870.

IMPROVED LADDER.

The Schedule referred to in these Letters Patent and making part of the same.

To all whom it may concern:

Be it known that I, JOHN A. THOMPSON, of Auburn, in the county of Cayuga and State of New York, have invented certain new and useful Improvements in Round and Step-Ladders; and I do hereby declare that the following is a full, clear, and exact description thereof, reference being had to the accompanying drawings making a part of this specification, and to the letters of reference marked thereon, like letters indicating like parts wherever they occur.

To enable others skilled in the art to construct and use my invention, I will proceed to describe it.

My invention consists in certain improvements in round and step-ladders, whereby greater lightness is secured, and their strength is increased.

Figure 1 is a perspective view of a round-ladder.

Figure 2, a similar view of a step-ladder.

Figures 3 3, view of metallic locks.

Figure 4, view of back braces.

Figure 5 shows the mode of attaching cord.

To secure lightness, I construct the rails of my ladder A A of angle form, sawing out a portion of the wood, as seen in figs. 1 and 2. For the same purpose I split the plank for the step, as shown in fig. 2, H H, thus increasing their strength in front when the weight is applied in ascending and descending, leaving the back of the step thin and light. The step and round are framed to fit the angle of the rail, as seen in figures, and locked to the rails by means of the metal corner locks L L, which are held to step, round, and rail by wood screws O passing through the rail and lock and into the round or step. The lock is secured to step and round on their under sides, making a firm support for the round and step, and binding the rail and step firm without weakening the rail.

To add to the strength of long step and round ladders, I spring a cord, J, of fine-twisted wire from top to bottom upon the back of the ladders, as shown at fig. 1, J. This cord is made tense by passing over suitable saddle pillars I, rising from the rail of the lad-

ders, and braced and tied by cross-ties, so the cords cannot be thrown off while the weight is applied.

As a security while ascending or descending long ladders, I attach firmly to the top of the outer rails of the ladder similar metal cords, of greater length than the rails, armed with suitable grappling hooks or pins, by means of which the lower ends of the stay cords may be held firm to the earth or to buildings, thus securing the ladder from falling sidewise or forward.

The back braces of the step-ladders, B, are also made of rails, constructed similar, and may be hinged as shown in fig. 4, with double-acting hinges, or by passing a rod from brace to brace on top, and applying the hinge to the outside of the braces. These braces are spread out or closed, and held by means of the curved ties, lock, and pin.

Having thus described my invention,

What I claim is —

1. In a round or step-ladder, the angle bars or rails, whether made of wood or metal, when arranged for the reception and support of the round or step, as and for the purposes set forth.

2. In combination with the described bars and the rounds or steps, the metallic lock rests, when constructed as and for the purposes set forth.

3. The described round and step-ladder, composed of the angle bars A, rounds H' H' or steps H H, with the described lock rests, all constructed and arranged as and for the purposes set forth.

4. The peculiar construction of the steps H H from a simple plank, when arranged with the thick edges on the front side, for the purposes set forth.

5. The described ladders, composed of the side bars A, steps H, lock rests L, hinged braces, with their adjustable cross-connections C C, and double-acting hinges M, all arranged and operating as and for the purposes set forth.

Witnesses: JOHN A. THOMPSON.

EDM. F. BROWN,

C. BESTOR.
